UNITED STATES PATENT OFFICE.

ALBERT GALLATIN, OF NEW YORK, N. Y.

DESIGN FOR A TELEPHONE-STANDARD.

41,685.

Specification for Design.

Patented Aug. 15, 1911.

Application filed February 19, 1910. Serial No. 544,955. Term of patent 14 years.

To all whom it may concern:

Be it known that I, ALBERT GALLATIN, a citizen of the United States, residing in the city, county, and State of New York, have invented a new, original, and ornamental Design for Telephone-Standards, of which the following is a specification, reference being had to the accompanying drawing, forming part thereof.

The figure is a perspective view of a telephone standard showing my new design.

The salient features of the design consist

in the enlarged upper member *c* and the pedestal member *a*, said members *a* and *c* being ornamented with related portions of a unitary decorative design.

I claim:

The ornamental design for a telephone standard, as shown and described.

ALBERT GALLATIN.
